UNITED STATES PATENT OFFICE

105,027

DESIGN FOR A TRANSPARENT CONVEX GLASS FOR PICTURE FRAMES

Harry J. Moravek, St. Louis, Mo.

Application January 28, 1935, Serial No. 55,110

Term of patent 14 years

To all whom it may concern:

Be it known that I, Harry J. Moravek, a citizen of the United States, residing at St. Louis, Missouri, have invented a new, original, and ornamental Design for a Transparent Convex Glass for Picture Frames, of which the following is a specification, reference being had to the accompanying drawing forming part thereof.

Fig. 1 is a perspective view of a transparent convex glass for picture frames embodying my new design.

Fig. 2 is a central vertical section therethrough.

Fig. 3 is a horizontal sectional view, on the line 3—3 of Fig. 2.

Fig. 4 is a similar view on the line 4—4 of Fig. 2.

The essential feature of the invention resides in the glass for picture frames being convex throughout its area with a point of greatest convexity approximately one third of the distance down from the top of the glass and merging into a less convex portion which extends downwardly therefrom to the lower edge of the glass, as shown.

I claim:

The ornamental design for a transparent convex glass for picture frames substantially as shown and described.

HARRY J. MORAVEK.
